UNITED STATES PATENT OFFICE.

ALFRED IRELAND, OF NEW YORK, N. Y.

DESIGN FOR AN ORNAMENT FOR GARMENTS.

40,682.

Specification for Design.

Patented May 3, 1910.

Application filed February 3, 1910. Serial No. 541,940. Term of patent 3½ years.

To all whom it may concern:

Be it known that I, ALFRED IRELAND, a citizen of the United States, residing in the city of New York, borough of Manhattan, in the county and State of New York, have invented a new, original, and ornamental Design for an Ornament for Garments, of which the following is a specification, reference being had to the accompanying drawing, forming a part thereof.

The figure is a plan view of an ornament for garments, showing my new design.

I claim:

The ornamental design for an ornament for garments, as shown.

ALFRED IRELAND.
